COMBINED DESK AND STORAGE UNIT

Fred A. Schmitt, Nutley, N.J., assignor to Litton
Business Systems, Inc., New York, N.Y.

Filed Jan. 4, 1971, Ser. No. 103,958

Term of patent 14 years

Int. Cl. D6—04

U.S. Cl. D6—162

FIG. 1

FIG. 2

FIG. 3

FIG. 4

FIG. 1 is a front perspective view of a combined desk and storage unit showing my design;

FIG. 2 is a view in front elevation thereof;

FIG. 3 is a perspective view of a modified form of the combined desk and storage unit shown in FIG. 1; and

FIG. 4 is a view in front elevation thereof.

The undisclosed sides of the unit are mirror images of the sides shown while the back surfaces are plain and unornamented.

I claim:

The ornamental design for a combined desk and storage unit, as shown and described.
